UNITED STATES PATENT OFFICE.

SAHATIEL G. MANDALIAN, OF NORTH ATTLEBORO, MASSACHUSETTS.

DESIGN FOR A GIRDLE.

Application filed January 27, 1922. Serial No. 407. Term of patent 7 years.

To all whom it may concern:

Be it known that I, SAHATIEL G. MANDALIAN, a citizen of the United States, residing at North Attleboro, in the county of Bristol and State of Massachusetts, have invented a certain new, original, and ornamental Design for a Girdle, of which the following is a specification, reference being had to the accompanying drawings, forming part thereof.

I claim:

The ornamental design for a girdle, as shown.

SAHATIEL G. MANDALIAN.
